UNITED STATES PATENT OFFICE.

ZACHARIUS O. FISCHER, OF MOCCASIN, MONTANA.

RAILWAY-SPIKE.

1,133,947.

Specification of Letters Patent. Patented Mar. 30, 1915.

Application filed May 11, 1914. Serial No. 837,841.

To all whom it may concern:

Be it known that I, ZACHARIUS O. FISCHER, a citizen of the United States, residing at Moccasin, in the county of Fergus and State 5 of Montana, have invented certain new and useful Improvements in Railway-Spikes, of which the following is a specification.

An object of this invention is the provision of a spike specially designed for securing railway rails to ties and embodying a novel and efficient locking means for positively preventing the removal of the spike from the tie.

Another object is the provision of a spike 15 of simple and efficient construction which shall be inexpensive to manufacture.

With these and other objects in view, the invention consists in the novel construction, arrangement and combination of parts as 20 will be hereinafter specifically described, claimed and illustrated in the accompanying drawings, in which,

Figure 1 represents a front elevation of the improved spike, and, Fig. 2 represents 25 a side elevation thereof, partly broken away, as applied to use.

Referring to the drawing in detail, where-in similar reference numerals designate corresponding parts throughout the several 30 views, the numeral 5 indicates the body of the spike having one end 6 beveled to provide a cutting edge and carrying a laterally projecting head 7 at the opposite end. An opening 8 is formed longitudinally through 35 the spike body 5 from the head 7 to a point nearly adjacent the longitudinal center thereof, and the inner end of said opening communicates with a second opening 9 extending transversely to that face of the 40 body from which the head 7 projects.

A locking member 10 is positioned within the open end of the transverse opening 9 and is of substantially wedge shape having the inner corner of the large end rounded, 45 as indicated at 11. The small end of the wedge shaped locking member 10 is pivotally supported in the open end of the opening 9 on a pin 12 positioned through the walls of the opening and transversely of the 50 body of the spike. In its normal position, as indicated in full lines in Fig. 2, the locking member 10 lies flush with the front face of the spike body 5 and obviously offers practically no resistance to the movement of

the spike as it is driven into the tie or other 55 object 13.

After the spike is driven the desired distance into the object 13, it is desirable to swing the locking member 10 outwardly and laterally of the spike to insure against the 60 removal of the spike. For this purpose, I provide a rod 14 preferably of cylindrical formation and having its lower end 15 pointed and carrying a suitable head 16 at its opposite end. The length of the rod 14 65 from the head 16 to the pointed end 15 is preferably equivalent to the distance between the top face of the head 7 of the spike and the inner end of the longitudinal opening 8, whereby the rod 14 practically closes 70 said longitudinal opening when the same is driven inwardly until the head 16 thereof engages the head 7 of the spike. During the inward movement of the rod 14 the pointed end 15 thereof engages between the wall of 75 the longitudinal opening 8 and the adjacent face of the locking member 10 and forces the latter outwardly to the position indicated by dotted lines in Fig. 2 where it is held as long as the rod 14 remains in operative position. The locking member 10 projects laterally of the body and from the same side as the head 7 and thus reliably holds the latter in firm engagement with the rail or other object.

It is clearly apparent that as the locking member 10 is moved laterally by the action of the rod 14 it is struck into the fibers of the tie 13 and greatly resists outward movement of the spike 5 due to vibration or any 85 other cause. It is also clearly apparent that, when necessary, the spike may be removed by withdrawing the rod 14 and thus permitting the locking member 10 to swing inwardly within the transverse opening 9 90 where it offers comparatively no resistance to the removal of the spike.

What I claim is:—

In a spike, a body, a head projecting laterally of the front face of said body, said body having a longitudinal opening extending from the headed end to a point adjacent the center thereof and having a transverse opening extending inwardly from the front face to and communicating with the 100 inner end of said longitudinal opening, a 105 wedge shaped locking member having its small end arranged adjacent said head and

pivottally secured in said transverse opening, the outer face of said locking member normally lying flush with the front face of said body and having an inner cam face, a rod 5 slideable longitudinally through said longitudinal opening having a pointed end adapted to engage the cam face of said locking member to swing the latter laterally of the

front face of said body, and a head on said rod adapted to engage the head of said spike. 10

In testimony whereof I affix my signature in presence of two witnesses.

ZACHARIUS O. FISCHER.
